(57) **CLAIM**

The ornamental design for a feline play structure, as shown and described.

DESCRIPTION

FIG. 1 is a perspective view of the invention;
 FIG. 2 is a front elevation view;
 FIG. 3 is a rear elevation view;
 FIG. 4 is a right side elevation view;
 FIG. 5 is a left side elevation view;
 FIG. 6 is a top plan view; and,
 FIG. 7 is a bottom plan view.
